UNITED STATES PATENT OFFICE.

FRED WAITE, OF OTLEY, ENGLAND.

FEED MECHANISM FOR PRINTING MACHINES.

Application filed June 18, 1923. Serial No. 646,103.

To all whom it may concern:

Be it known that I, FRED WAITE, a subject of the King of Great Britain, and resident of Inglewood, Otley, in the county of York, England, have invented a certain new and useful Improvement in Feed Mechanism for Printing Machines, of which the following description, having reference to the accompanying sheets of drawings, is a specification.

In the printing of envelopes, cards, sheets of paper and the like, which vary considerably in thickness and which are to be detached singly from a pile to be fed to the printing machine, difficulty is experienced in detaching each single envelope (or the like) from the pile and many and varied methods have been followed in carrying out this detaching and separating process. My present invention consists in the production of novel means for separating or detaching said envelopes whether same are comparatively thick or bulky or are thinner, that is to say, whether the envelopes are comparatively thick envelopes or the cards are comparatively thick cards or are thin cards or paper and these functions I perform with the greatest precision so that each one is fed to the printing machine and bundles of supplies may be placed in the hopper by the attendant during and without stopping or arresting the motions of the machine. My said method of selection, while bringing each envelope, card or the like into position for enabling said envelope, card or the like to be gripped and carried forward to the other parts from which it is fed to the printing machine entirely prevents such envelope or card from disarranging the other cards in the pile. Further than this the registering of the envelope, card or the like on the feed plate and the detaching of same, so that on its absence the impression may be checked, are effectively performed by devices operating in conjunction with the other parts of my improved mechanism.

In order that my said invention may be better understood, I have hereunto appended sheets of drawings illustrative thereof in which:—

Fig. 1 is a side elevation showing my improved mechanism as applied to a platen printing machine, and with the suction apparatus in engagement with the lowest envelope or card in the pile.

Fig. 2 is a similar view to Fig. 1, but illustrates the same parts of the machine moved into their respective relative positions after the suction nozzles have detached the lowest card from the pile.

Fig. 3 is a similar elevation to Fig. 1 but shows certain of the parts drawn to an enlarged scale in order better to illustrate the several positions they assume.

Fig. 4 is a similar view to Fig. 2 but shows certain of the parts drawn to an enlarged scale.

Fig. 5 is a similar view to Figs. 1 and 2, but shows the positions of certain parts when delivering the card or envelope into the place where the other parts of the machine are encountered to take same forward to carry out the printing process, said figure being drawn to same scale as are Figs. 3 and 4.

Fig. 6 is a side elevation but shows devices which are used in connection with those shown by the other figures for adjusting the card in position prior to the grippers of the printing machine carrying same forward to undergo the printing operations.

Fig. 7 is a plan of parts shown by Fig. 6.

Fig. 8 is a plan of the feed table and parts mounted upon it.

Fig. 9 is a side elevation showing the gripping devices and means for operating same according to my invention. These devices are drawn to a still larger scale.

In accordance with my invention I make use of a chute, shoot or hopper 2 into which I feed a bundle or pile of envelopes, cards or sheets of paper 3 (hereinafter referred to as cards) so that the same may descend down through said shoot 2 by said shoot 2 being arranged at an appropriate angle to the horizontal plane to permit the cards to descend through it by gravity while yet supporting a great part of the weight of said cards by the base of the shoot.

At the lower end of the shoot 2 a cross piece or plate 4 is mounted so that it will reach from the base of the shoot sufficiently high to retain the cards 3 within the shoot 2 behind it. The upper edge *a* of the plate is preferably situated at about the middle part of the cards or slightly higher while over the top of the shoot 2 a plate 5 is mounted to overhang the cards beneath and to extend beyond the lowest card in the shoot 2 so that all the upper edges of said cards are covered by said plate 5 until after

their selection and detachment as is hereinafter described and as is shown by Figs. 2 and 3.

- Adjoining the cross plate 4 at the base 5 of the shoot 2 are mounted a series of suckers 6 which derive their suction from an appropriate exhaust pump 7 (or from any well known source) and these suckers 6 are mounted upon arms 8 which are fixed upon 10 an oscillating shaft 9 so that as said shaft 9 oscillates the surfaces or nostrils of the suckers 6 may be presented to the surface of the lowest card 3 and in a position over and above the cross plate 4 as shown by 15 Figs. 1 and 3 in order that on the moving of the suckers 6 into their positions shown by Fig. 2 the upper part of the lowest card 3 is bent and separated or divided from the other cards behind it as is shown by Figs. 2 20 and 4. This bending of the upper part of the card has the effect of bringing the upper edge thereof from beneath or clear of the cover 5 which extends across the shoot 2 as above described.
- 25 The centre of oscillation of the arms 8 which carry the suckers 6 is so situated relatively to the point at which the bending of the card takes place (which bending is near or about the upper edge of the plate 4) 30 that said centre of oscillation is approximately coincident with, or to the rear of, the line where the bend of the cards is made when the nostrils 6 are moved through their curved path thus the moving of the card is 35 under such conditions that the surface contacts of the nostrils 6 are not disturbed hence the suction actions are not interfered with but are enabled to act with the greatest precision.
- 40 In conjunction with the suction devices described I make use of grippers 10 (see Fig. 3) which I mount upon oscillating arms 11 by means of a cross shaft 12 mounted upon lever arm 13. These arms 13 are the 45 quadrant extensions of levers 13^a fixed upon the oscillating shaft 14 one of said lever arms 13^a with its quadrant part 13 being on one side of the machine while there is a similar arm and quadrant on the other 50 side of the machine.
- 55 On the shaft 12, upon which the gripping devices 10 are mounted is also fixed the toothed quadrant 11, and this quadrant 11 is made to mesh with another toothed quadrant 15 pivoted on the quadrant arm 13. The grippers 10 are caused to open by the bowl on the arm of the lever 15 coming into contact with a pivoted incline 15^a which causes the grippers to open towards the end of 60 their forward movement and to continue open till the end of that stroke, when the incline 15^a is permitted to descend (by the raised part of its operating cam 15^b moving beyond the bowl 15^c which is carried by the lever 15^a to which 65 lever the incline 15^a is connected by the rod

15^c) so that the lever 15 is moved by the recoil of the spring 10^a and this lever operates the lever 11 and closes the grippers 10, as is shown by Fig. 9.

These grippers 10 will at this time have 70 laid hold of the edge of the envelope or card and will therefore retain such hold until the arms 13^a have carried said grippers and the envelope or card to the opposite end of their path as shown by Fig. 5. On 75 reaching this end of their path the bowl on the lever 15 will encounter another incline 15^f (Fig. 2) which is mounted on the horizontal arm of the lever 15^g by which incline 15^f the grippers 10 are opened so as 80 to deposit their envelope or card upon the feed table 16 beneath.

The lever 15^g is operated by the bowl on its pendant arm being in contact with the cam 15^h on the oscillating shaft 14. The 85 lever 15^g is shown by Fig. 2 in its proper relative position with the grippers 10 when these are at the end of their path away from the incline 15^f so that although said incline 15^f is shown in a raised position it is 90 brought to its proper position on the approach of the grippers in order that it may act upon the lever 15 and its said movement as effected by the lever 15^g is only employed in order to carry same out of the path of the well known oscillating member 15^k.

The arms 13 and quadrant portions 13^a are mounted on each side of the machine but within the two end frames A A¹ so that they 100 do not interfere with any of the other operating parts of the apparatus whether such apparatus is for use in conjunction with a platen or other printing press.

However, when my improved devices are 105 used in connection with a platen printing machine in order to be enabled to apply same thereto as stated without interfering with the other and well known operating parts of the machine, I arrange the radiating portions 13^a of the arms to have quadrant parts 13 extending from them in order that I may 110 be able to mount thereon the cross bar 12 in such position that the grippers 10 carried by it are brought into position for gripping the card when the radial arms 13 are 115 in their lowest positions as shown by Figs. 2 and 3. By this arrangement when the arms 13 oscillate the curved quadrant parts 13^a of said arms (which are in the form of the arc of a circle the centre of which is the centre of oscillation of the shaft 14) will travel over the feed plate 16 of the machine as is shown by Fig. 5, without coming in contact with the edge of said feed plate 16, and when in this position the grippers 10 120 are caused to deliver or release their hold of the card and deposit same upon the feed plate 16 as before explained.

When the grippers 10 have deposited the 125 card upon the feed table 16 then the card or 130

sheet adjusting devices hereinafter described are brought into use to register said card longitudinally and laterally so that same is brought with its edge over the openings 5 16^a in the feed plate 16 and in exact position for the grippers of the printing apparatus to lay hold thereof in order to carry same forward for the printing process to be carried out.

10 This adjustment of the card or sheet upon the feed table 16 is effected by the sliding adjusting plates 17, 17^a mounted upon said feed plate 16. These sliding adjusting plates 17, 17^a are normally held by their respective springs *b* in a rearward position so that by having mounted on their outer ends runners or bowls *c* they may be caused to move and approach each other by the actions of the advancing inclined ends of arms 20 *d*, *d*¹. These arms *d*, *d*¹ extend from a bar 18 that is mounted to slide upon the feed table 16 when acted upon as is hereinafter described.

The bar 18 is retained in its rearward normal position by means of retracting springs *f* before it is moved forward to actuate the sliding plates 17, 17^a.

15 The sliding bar 18 is actuated and forced toward the notches 16^a of the feed plate 16 by means of the sliding connecting rods 19, 19^a one of which is mounted on one side, the other on the other side of the machine and are pivoted upon the respective arms 20, 20^a which are fixed upon a shaft 22, upon 30 which is fixed the lever 21.

20 The shaft 22 is the one well known as the frisket shaft of the machine and this frisket shaft derives its name by reason of carrying flat bars 23 (which are called friskets) that 40 are used to hold down the edges of the cards on the platen face and which bars are adjustably mounted upon said shaft 22 in a manner well known. As the rods 19, 19^a slide from right to left as actuated by their 45 levers the hooked or laterally projecting arms 24, 24^a extending from them have their lower ends arranged to come in contact with the cross sliding bar 18 at each side of the machine as shown by Fig. 5, thus as the 50 frisket shaft oscillates so do the sliding bars 19, 19^a oscillate and at such proper relative times to cause the cross bar 18 to advance and move the card into position over the slots 16^a of the feed plate and leave 55 same in the exact position desired while at the same time the movement of the cross bar 18 will have caused the adjusting plates 17, 17^a to move towards each other to adjust the position of the card laterally in order 60 that it may be taken forward and held in the exact position desired during the subsequent printing process.

65 In connection with the foregoing devices I make use of detector mechanism for checking the actions of the machine pro-

vided there is no card deposited on the feed table 16.

On account of the comparatively short space of time in which the detector lever has to perform its functions I have found 70 that when its detecting end is permitted to descend into action under gravity alone, its said actions are very uncertain. To avoid this I make use of a detector 25 of a comparatively light construction and I couple 75 its operating shaft 26 by lever arms 27 to a spring actuated lever 28 said lever 28 being fixed upon a cross shaft 29 to which is fixed a lever 30 operated by a spring 31 thus by its descent under the actions of said 80 spring 31 the detector lever 25 is caused to descend under the control of devices hereinafter described.

The detector shaft 26 has mounted upon it a lever 32 which extends vertically so that an antifriction bowl *h* mounted upon it, may be in contact with an oscillating lever 33. This oscillating lever 33 is pivoted to the framework A and derives its motion through the connecting rod 34 and lever 35 upon the arm 35^a, of which is mounted an antifriction bowl *h* arranged to come in contact with so as to be operated by a cam 36 fixed upon one of the main shafts 37 of the machine.

85 The lever 35 is enabled to keep its antifriction bowl *h* in contact with the periphery of the cam 36 through the actions of the retracting springs 38.

90 As will be observed the cam 36 by rotating 100 in the direction indicated by the arrow *m* will at one time raise the detector 25 and will at another time allow said detector to descend under the recoil of its retracting spring 31 until the position is reached where the detecting surface 25^a of the detector lever 25 is just approaching the position shown by Fig. 4 in which it will be only a short distance from the surface of the card upon the feed plate 16.

105 When this position is reached the stop piece 39^a on the lever 33 comes in contact with the edge of the end frame so that the further movement of the lever 38 is arrested, while the cam 36 will still move forward and immediately permit the runner *h* to move nearer its centre of rotation and therefore to move the lever 35 and consequently the lever 33 clear of the antifriction bowl *h* in order to permit the shaft 26 110 to still move forward under the weight of the arm 25 hence this detector arm will descend through the small space described under its own weight and therefore will 115 contact with the card beneath under such conditions as not to damage said card and in sufficient time to indicate by its checking actions to permit the motions of the machine to continue. Provided, however, 120 there is no card present then the detector 125

end 25^a will pass below the feed table 26 and cause the impression to be checked by the actions of the lever 50 (which is fixed upon the shaft 26) in well known manner.

5 On the grippers having deposited a card upon the feed table and said card has been adjusted in position so that the grippers from the printing mechanism lay hold of same to carry it forward so that it may be 10 subjected to the printing process, the grippers 10 will commence to recede and return to their former position shown by Fig. 3 and at such time the printing grippers will have removed the card from the table 16 15 and will have carried same forward as will be understood.

The sliding plates 17, 17^a which are for adjustment of the cards in a lateral direction have projections extending above them 20 to carry out such adjustment and these projections may be adjusted in slots formed longitudinally in said bars 17, 17^a to meet the requirements of the length or width of the card.

25 The shoot 2 is arranged so that its base 41 may be raised or lowered to meet the requirements of broader or narrower cards that have to be supplied by it, while the side walls of the said shoot or hopper are also 30 adjustable in order that they may permit longer or shorter cards to be guided by them.

The cross piece or stop plate 4 at the base of the shoot is also made adjustable so that 35 the position of its upper edge may be regulated according to the depth or width of the cards that have to be fed to the machine.

As before stated, the invention is adapted 40 for feeding envelopes, cards or sheets of paper. For convenience, any or all of such articles are to be understood as included in the term "sheets" employed in the following claims.

Such being the nature and object of my 45 said invention, what I claim is:—

1. In a mechanism for the purpose described, the combination of a hopper adapted to support a series of sheets so that they will project above the upper edge of a 50 stop at the lower end of the hopper, a rock shaft, a sucker supported by said shaft and adapted to be positioned to contact with the portion of the lowest sheet in the hopper that extends beyond said stop and bend 55 said portion of the sheet along the edge of said stop as the shaft is rocked, a second rock shaft, arms extending laterally from said shaft toward the hopper and curved so that their free ends are directed rear- 60 ward from the hopper, a gripper carried by said arms and adapted to engage the bent edge of the lowest sheet in the hopper and withdraw such sheet from the hopper as the shaft rocks, and means for automatically 65 disengaging the sheet from the gripper

as the latter approaches the limit of its movement away from the hopper.

2. In a mechanism for the purpose described, the combination of a hopper adapted to support a series of sheets so that they will project above the upper edge of a stop at the lower end of the hopper, a rock shaft mounted on an axis adjacent and substantially parallel to the free edge of said stop, a sucker supported by said shaft and adapted to be positioned to contact with the portion of the lowest sheet in the hopper that extends beyond said stop and bend said sheet along the edge of the stop as the shaft rocks, a second rock shaft, a gripper supported by the last said shaft and adapted to engage the bent edge of the lowest sheet in the hopper and withdraw such sheet from the hopper as the gripper supporting shaft oscillates, and means for automatically releasing the withdrawn sheet from the gripper as the latter approaches the limit of its movement away from the hopper.

3. In a mechanism for the purpose described, the combination of a hopper adapted to support a series of sheets so that they will project above the upper edge of a stop at the lower end of the hopper, a rock shaft, a sucker supported by said shaft and adapted to be positioned to contact with the portion of the lowest sheet in the hopper that extends beyond said stop and bend said portion of the sheet along the edge of said stop as the shaft is rocked, a second rock shaft, two arms projecting from the last said shaft and extending toward the hopper, said arms being spaced sufficiently to pass on opposite sides of the hopper, a shaft journaled in said arms adjacent the free ends thereof, a gripper jaw mounted on each end of said shaft, a second gripper jaw pivotally mounted on each lever and adapted to co-operate with the adjacent gripping jaw on the shaft, means for rocking the second said rock shaft to carry the grippers to and from a position to engage the bent edge of the lowest sheet in the hopper, means for rocking the pivoted gripping jaws as they approach the hopper to separate the jaws to permit them to receive the bent edge of the lowest sheet in the hopper, means for closing the jaws upon said sheet, and means for disengaging the sheet from the gripping jaws as the latter approach the limit of their movement away from the hopper.

4. In a mechanism for the purpose described, the combination of a hopper adapted to support a series of sheets, a substantially horizontal rock shaft, an arm carried by the rock shaft, a gripper supported by said shaft and including a pivotally mounted jaw, the parts being so arranged that as the shaft oscillates the gripper will be carried toward and from the hopper, a pivotally mounted cam adapted to rock the pivot-

ed gripping jaw to open position as the gripper approaches the hopper, means for positively swinging said cam from position to engage said jaw as the gripper receives the lowest sheet in the hopper, and means for automatically disengaging the sheet from the gripper as the latter approaches the limit of its movement away from the hopper.

5. In a mechanism for the purpose described, the combination of a hopper adapted to support a series of sheets, a substantially horizontal rock shaft, arms projecting from said shaft toward the hopper, a rock shaft journalled in said arms near the 10 free ends thereof, a gripping jaw secured to said rock shaft, a second gripping jaw pivotally mounted on one of the levers and having a toothed engagement with a member on the shaft whereby said jaw and shaft will be 15 rocked in unison, a cam normally extending into the path of the pivotally mounted jaw so that the jaws will be separated as they 20 approach the hopper, positive means for withdrawing said cam from the path of the gripping jaw to permit the jaws to close upon the lowest sheet in the hopper, and a second cam adapted to engage the pivotally 25 mounted jaw to actuate it to disengage the sheet as the gripper approaches the limit of its movement away from the hopper.

withdrawn sheet from the gripper as the latter approaches the limit of its movement away from the hopper.

6. In a mechanism for the purpose described, the combination of a hopper adapted to support a series of sheets, a substantially horizontal rock shaft, arms projecting from said shaft toward the hopper, a rock shaft journalled in said arms near the free ends thereof, a gripping jaw secured to said rock shaft, a second gripping jaw pivotally mounted on one of the levers and having a toothed engagement with a member on the shaft whereby said jaw and shaft will be 30 rocked in unison, a cam normally extending into the path of the pivotally mounted jaw so that the jaws will be separated as they 35 approach the hopper, positive means for withdrawing said cam from the path of the gripping jaw to permit the jaws to close upon the lowest sheet in the hopper, and a second cam adapted to engage the pivotally 40 mounted jaw to actuate it to disengage the sheet as the gripper approaches the limit of its movement away from the hopper.

FRED WAITE.
